CLAIM

The ornamental design for a golf ball placement marker, as shown and described.

DESCRIPTION

FIG. 1 is a front elevational view of a golf ball placement marker showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a perspective view thereof.

The broken line showing of the numbered paper and grass in FIG. 7 is for illustrative purposes only and forms no part of the claimed design.
